(57) **CLAIM**

I claim the ornamental design for a bottle adapter, as shown and described.

DESCRIPTION

FIG. 1 is an exploded perspective view of a bottle adapter shown in a used condition with a thermos bottle and manual sprayer showing my new design;

FIG. 2 is a perspective view of a bottle adapter shown in another used condition with a thermos bottle and manual sprayer;

FIG. 3 is a front elevational view of a bottle adapter;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an alternate perspective view thereof.

The broken lines showing a thermos bottle and a manual sprayer in FIGS. 1 and 2 are included for the purpose of illustrating the invention in use, and form no part of the claimed design.
